UNITED STATES PATENT OFFICE

2,029,321

FEED WATER REGULATOR

William L. Hunter, Erie, Pa., assignor to Northern
Equipment Company, Erie, Pa., a corporation

Application January 6, 1934, Serial No. 705,519

13 Claims. (Cl. 122—451.1)

This invention relates to apparatus for feeding water to boilers, and it has for its object providing automatic means for feeding the water which are responsive to the operation of the boiler, and also providing manual means which may be operated in place of the automatic means when desired for any reason. A particular feature of the invention is the provision of a feed-water valve which is common to both the automatic and the manual means, and for providing additional means for operatively connecting the manual means to the valve and at the same time rendering inoperative the automatic means.

Other objects of the invention will be apparent from a consideration of the accompanying drawings and the following description thereof.

Of the drawings, Fig. 1 is an elevation of a boiler system which embodies features of my invention; Fig. 2 is an elevation much enlarged and partly in section of the feed-water valve of the system and a portion of the operating means therefor; Fig. 3 is a similar elevation at 90° to Fig. 2; Fig. 4 is a further enlarged elevation of the manual operating means; Fig. 5 is a sectional view along the line 5—5 of Fig. 4; Figs. 6 and 7 are sectional views along the line 6—6 of Fig. 4, Fig. 6 showing the manual means operative and Fig. 7 showing the manual means inoperative; Fig. 8 is an elevation corresponding to Fig. 2 of a modified form of apparatus; and Fig. 9 is a plan view of the apparatus shown in Fig. 8.

In the operation of boilers, it is usual to provide a feed-water regulator which is responsive to the operation of the boiler for operating the feed-water valve. In certain cases, however, particularly in the operation of boilers on vessels, it becomes necessary or desirable at times to feed the water to the boiler manually and perhaps to render inoperative the feed-water regulator. The present invention provides both automatic and manual means for feeding water to the boiler, and it is particularly directed towards the use of a single feed-water valve which may be operated by either the manual or the automatic means, and when so operated the other means is inoperative.

Any type of automatic means may be used for operating the feed water valve, such as any of the ordinary feed-water regulators; but I prefer for the purpose of illustrating this invention the thermostatic type of feed-water regulator which is in common use and which consists of a tube 10 which is operatively connected to the boiler 11 above and below the normal water level there-

in. This connection may be made by means of pipes 12 and 13 connected respectfully to the ends of the tube and to the boiler above and below the normal water level therein. A feed-water valve 14 is provided and which is operatively connected to the thermostatic tube in any suitable manner. In this case I provide a lever 15 connected to the tube and its frame and an arm 16 connected to the valve and a link 17 connecting the two members 15 and 16. As is well understood, in such a case, as the water in the boiler rises the tube will contract and the valve will be closed more, or when the water in the boiler sinks below a predetermined level the tube will expand and the connecting means will open 15 more the valve.

I provide also manual means for operating the valve 14. While variations in such means may be made, yet I prefer for the purpose a rod 20, having an operating handle 21, which is operatively connected to the valve in any suitable manner, preferably by means of the arm 16, so that the valve may be manually operated by the rod 20 so as to open or close more the valve as may be desired.

In order to prevent the manual operating means from interfering with the automatic means, or to prevent the automatic means from interfering with the manual means when the valve is to be manually operated, I prefer to provide the link 17 with tension means which will yield more or less as the arm 16 is pulled downwardly. I prefer for this means the casing 22 (Fig. 2) in which is slidably mounted a rod 23. The casing is pivoted to the arm 16 and the rod is pivoted to the lever 15 directly or indirectly. A spring 24, positioned between the upper end of the casing and an enlargement 25 on the rod, provides yielding means so that the arm 16 may be forced downwardly without affecting the lever 15.

In order to provide for moving the arm 16 upwardly when the apparatus is manually operated, any suitable means may be used. For this purpose I prefer to provide a flexible joint 26 which will allow the connecting link to move up more or less as the arm 16 is operated upwardly, without interfering with the lever 15. To insure this non-interference, a slot 27 may be provided which allows the pivot of the joint to play freely upwardly as the arm 16 is elevated manually. Another means for allowing the arm 16 to be elevated manually is to slidably mount the tube 10 in a frame 30 so that when the arm of the 55

lever 15 is moved upwardly the tube will slide to the right in the frame, as the tube is mounted for tension only by means of the lock nuts 31 which prevent movement of the tube to the left beyond a predetermined position.

The means which I provide for manually operating the valve comprises, in addition to the rod 20, a worm 32 (Fig. 4) mounted on the rod which meshes at all times with the gear wheel 33. The wheel is arranged to be connected to a shaft 34 which is rotatably mounted in the casing 37 and is operatively connected, by means of an arm 35 and a link 36, to the arm 16. So that when the rod 20 is rotated in one direction, the arm 35 will be elevated to elevate the arm 16 and will close more the valve; and when the rod 20 is rotated in the other direction, the arm 35 will be lowered to close more the valve.

With this arrangement, however, it is desirable to provide means for disconnecting the wheel 33 from the arm 35, so that when the valve is to be operated automatically there will be no interference by the wheel 33 and the worm 32 with the operation of the feed-water regulator. For this purpose I provide a clutch which comprises a disk 38 fixed to the shaft 34 and arranged to be locked to the wheel 33 whenever desired for manual operation, and to be released therefrom when the manual means is to be inoperative. To accomplish this I mount the shaft 34 slidably in the casing 37 and provide a rod 40 for operating the clutch. Any suitable clutch and operating means therefor may be used, but I prefer for the purpose a clutch which comprises a roughened surface 41 which is adapted to coact with a similar surface 42 on the gear wheel 33.

When these two surfaces are thrown together, the clutch will be operative and when they are separated the clutch will be inoperative. To force the surfaces together, I provide an eccentric pin 43 fixed to the upper end of the rod 40. The pin is adapted to be operated in an oval opening 44 in a member 45 fixed to the rod 46. The rod 46 is rotatably but non-slidably mounted in the shaft 34, preferably, as indicated, by means of a nut 47 on the end of the rod. When the rod 40 is rotated to a certain position, the pin will be in the position indicated by the Figs. 5 and 6, and the clutch members will be closed, and when the rod 40 is rotated through 180° the pin will be in the position indicated in Fig. 7, and the clutch members will be separated. A consideration of Figs. 6 and 7 will show that when the clutch members are separated the shaft 34, together with the arm 35 and the bearings 50 and 51 and the disk 38 will be forced downwardly; and these members will all be forced upwardly when the clutch is closed. The clutch may be locked in either its closed or its open position by means of a pin 48 in the slot 49.

It will thus be seen that I have provided both automatic and manual means for operating the same feed-water valve. In order to render the automatic means inoperative, it is necessary only to rotate the rod 40, by means of the arm 21, through 180° from the normal operating position. The valve may then be operated manually entirely independently of the automatic means so as to entirely open or close the valve, or to position it wherever desired. When it is desired to return to automatic operation, it is necessary only to rotate the rod through 180° and the manual means will be entirely disconnected.

A result of the arrangement described is that the automatic means will be in no way perma-

nently affected by the manual operation of the valve. When the clutch is separated, if the arm 16 has been elevated by the manual means above the normal operating position, the arm will at once be pulled downwardly by the spring 52 to the proper position for automatic operation. This spring will force the link connecting the arm 16 and the lever 15 to the normal operating positions, and if the tube 10 has been forced to the right, it will be pulled to the left until stopped by the nuts 31. As a consequence the tube will take up its work exactly the same as if it had not been interfered with by the manual operation, positioning the feed-water valve so as to feed water according to the needs as indicated by the water level in the boiler. If the arm 16 has been pulled downwardly beyond the normal position, when the clutch is released the spring 24 will at once force the arm 16 up to the proper normal position so that the automatic means will then control the flow of water to the boiler exactly as if it had not been rendered inoperative at all.

The use of manual operating means for controlling the valve may be desirable for many reasons; for instance, if the water in the boiler should inadvertently rise too high or sink too low. The operator will then manually operate the feed to the boiler until the level becomes normal. If the automatic means becomes inoperative for any reason, the operator can feed with the manual means so long as may be necessary.

A further feature of the means which I have illustrated comprises a valve 57 which is mounted in the casing of the feed-water valve. This valve may be seated on a seat 58, and may be operated by any means such as a rod 59 and a wheel 60. This provides a stop-and-check valve for any emergency in a very simple manner, as the same casing is used for both valves and the expense and room required for an additional outside valve is avoided. Obviously by the use of this valve both the automatic and the manual operating means may be very quickly rendered entirely inoperative; and furthermore this valve may be used to vary more or less the operation of the feed-water valve by providing an adjustable restriction from the valve to the boiler in the connecting passageway.

The particular type of feed-water valve which may be used in connection with my invention is not material, but I prefer to use a valve which is arranged so as to very sensitively and suitably control the flow of water to the boiler in accordance with the needs thereof. This valve preferably comprises a tube 61 in which is slidably mounted a plunger 62. The tube is fixed to the diaphragm 63 in the valve casing and the plunger 62 is fixed, by means of a rod 64 to the arm 65. This arm is fixed to the arm 16 by means of a rod 66, in an ordinary manner. As is well known, a valve of this nature is much better adapted to properly proportion the water feed than is any ordinary manually operated valve, and by controlling this valve by manual means the same effectiveness is arrived at as is the case when the valve is controlled automatically, subject to the uncertainties of ordinary manual control.

Although I have illustrated and described the valve 57 in connection with the feed-water valve, it will be understood that this valve 57 is not a necessary part of my entire invention, and this valve may be dispensed with. Figs. 8 and 9 illustrate the mechanism and the feed-water valve without the stop-and-check valve 57. In this case the operating mechanism is substantially

the same as has been herein described with reference to Figs. 2 and 3, and a detailed description thereof is unnecessary.

I claim as my invention:

- 5 1. Apparatus for feeding water to boilers, comprising a feed-water valve, means responsive to the operation of the boiler for operating the valve, manual means for positioning the valve without any interference by the responsive means.
- 10 2. Apparatus as claimed in claim 1, said responsive means being arranged to be entirely inoperative when said manual means are operative.
- 15 3. Apparatus for feeding water to boilers, comprising a feed-water valve, manual means for operating said valve according to water needs of the boiler, means for rendering inoperative said means, and automatic means for operating the valve when said manual means are inoperative.
- 20 4. Apparatus as claimed in claim 1, and additional means for varying the passageway through the casing of the valve.
- 25 5. Apparatus as claimed in claim 1, and means mounted in the casing of the valve for rendering the responsive and the manual means inoperative.
- 30 6. Apparatus for feeding water to boilers, comprising a feed-water valve, means responsive to the operation of the boiler operatively connected with the valve, manual means for operating the valve, and clutch means for operatively connecting the manual means to the valve.
- 35 7. Apparatus as claimed in claim 6, the valve comprising an operating member, and the responsive means and the clutch means each being successively operatively connected to said operating member.
8. Apparatus for feeding water to boilers, comprising a feed-water valve having an operating member, automatic means and manual means for operating the valve, yielding means for connecting the automatic means to the operating member, and clutch means for connecting the manual means to the member.
- 10 9. Apparatus as claimed in claim 8, and yielding means tending to force the valve to the open position.
- 15 10. Apparatus as claimed in claim 3, in which the relation of the responsive means to the valve is unchanged by the operation of the manual means.
- 15 11. Apparatus for feeding water to boilers comprising a valve manual means and also means responsive to the operation of the boiler, and means for successively connecting the manual means and the responsive means to the valve.
- 20 12. Apparatus for feeding water to boilers, comprising means responsive to the operation of the boiler, a feed water valve, means for operatively connecting said responsive means to the boiler, means for rendering inoperative said operatively connecting means, and manual means for operating said valve when said operatively connecting means are rendered inoperative.
- 25 13. Apparatus for feeding water to boilers comprising a feed water valve, boiler responsive means for operating said valve, manual means, normally inoperative, for operating said valve, and means for rendering operative said manual means and rendering inoperative said responsive means.

WILLIAM L. HUNTER.
